FEEDING MACHINE

Sigwald C. Grunlee, Chicago, Ill.

Application December 22, 1950, Serial No. 202,221

3 Claims. (Cl. 271—28)

The present invention relates to feeding and gathering machines of the type used primarily for an assembly operation in the mass production of magazines, books, catalogues and the like.

In the manufacture of books, magazines, catalogues and the like, in the interest of brevity referred to hereafter collectively as books, a group of individual units to be referred to as forms is collected in order. These forms may comprise anything from a single page to a number of pages folded at the center.

The portion of the machine which collects the several forms in proper order into piles, the piles later being stitched, and covered to form books, is commonly termed a gatherer and comprises essentially a constantly moving conveyor system having a row of isolated spaces or pockets into which the forms are piled. The conveyor with the pockets therein moves usually horizontally past a row of feeders, each feeder being charged with the responsibility of placing one of its forms in each pocket as it passes on top of the forms placed in the pockets previously by other feeders in the series.

The feeding mechanism therefore comprises a row of substantially identical feeders which must somehow be adjustable so that a particular feeder can be preset to feed a form of several pages, whereas another feeder in the same feeding machine may need to be adjusted to feed a single sheet, such as a color page, for instance. Frequently also the individual forms may be made of different kinds and qualities of paper and in addition, in order to have wide utility, the feeders and gatherer should be adjustable to assemble books of different page size.

Normally the gatherer will deliver the piles of forms at the end of its travel to other machines which staple or stitch the forms together, attach covers thereto, and trim the books to proper size.

The present invention is limited to the machine which includes the feeders and gatherer and therefore the additional machinery mentioned, which may be of any well known and suitable type, is not illustrated.

Most of the description which follows of the feeding portion of the machine will be directed to a single unit, termed a feeder, it being understood that such units are repeated in tandem as required, and that each unit functions in timed relation to a rotating shaft which drives all of the feeders and the gatherer so as to simplify the problem of synchronization. In the interest of economy, however, certain shafts which rotate or oscillate together in several adjacent feeders may be and in the present instance are continuous through several feeders. This avoids the necessity of duplicating much of the drive mechanism for these shafts in each individual feeder. In other instances these shafts are individual to a particular feeder because there otherwise would be interference among the machine elements, or because there may be differential movement between similar shafts on adjacent feeders.

It is one of the objects of the present invention to pro-

2

vide an improved feeding mechanism which has the advantage over prior feeders in that it may be operated at much higher speed and with less service difficulties and with greater ease.

Another object is to accomplish the above and in addition provide improved mechanism for stopping all of the feeders in the group and the gatherer in the event that one of the feeders makes a mistake or encounters a faulty form.

10 Yet another object is to provide a novel feeder and gatherer of the above type which is less likely to damage forms passing therethrough and is less sensitive to the number or condition of the forms in the pile from which it is feeding.

Still another object is to provide a feeder and gatherer of the above type which may be easily adjusted to handle forms of a wider variety of material, size, and thickness than feeders with which I am familiar and which will present the piles of forms to successive machines in better condition.

20 In general, therefore, it is an object to provide an improved feeder and gatherer which will perform all of the functions of prior feeders and gatherers but will accomplish these functions at much higher speed, with less supervision, with less danger that the assembled product will be faulty, and in addition will, through simple adjustment, perform these functions upon a wide variety of materials. In addition the arrangement is such as to provide for quick and easy adjustment, both of the 25 feeder and gatherer when shifting from one book assembly job to another.

Other objects and advantages will become apparent from the following description of a preferred embodiment of my invention which is illustrated in the accompanying drawings:

35 In the drawings, in which similar characters of reference refer to similar parts throughout the several views:

Fig. 1 may be considered as an end view of one of the 40 units of the machine and shows in elevation a single feeder and one unit of the gatherer. Only the longitudinally extending portions of the machine which pass from one unit to the next are shown in section.

Fig. 2 is a view similar to Fig. 1 but showing the 45 relationship of the feeder and gatherer drawn to larger scale;

Fig. 3 is a fractional elevational view showing the head of one unit of the gatherer drawn to larger scale. It may be considered as taken in the direction of the arrows along the line 3—3 of Fig. 2;

50 Fig. 4 is a longitudinal vertical sectional view of a portion of the gatherer and may be considered as taken in the direction of the arrows substantially along the line 4—4 of Fig. 2;

Fig. 5 is a horizontal sectional view showing a portion of the position adjusting mechanism of the head of one unit of the gatherer and is taken substantially along the line 5—5 of Fig. 2;

Fig. 6 is a sectional view showing the means for adjusting the trough components and may be considered as taken substantially along the line 6—6 of Fig. 4;

Fig. 7 is a longitudinal sectional view through a portion of the conveyor mechanism and is taken in the direction of the arrows along the line 7—7 of Fig. 2;

Fig. 8 is a fractional elevational view of a portion of the conveyor mechanism and may be considered as taken substantially along the line 8—8 of Fig. 10;

Fig. 9 is a view similar to Fig. 8 but taken from the opposite direction as indicated by the arrows along the line 9—9 of Fig. 10;

Fig. 17 is a fractional view drawn to larger scale showing in plan a portion of the form gripping and feeding structure;

Fig. 18 is a fractional view looking downwardly showing the form gripping and feeding mechanism in plan. It may be considered as taken in the direction of the arrows substantially along the line 18—18 of Fig. 12;

Fig. 19 is a view similar to Fig. 18 excepting that it is taken in a vertical plane in the direction of the arrows substantially along the line 19—19 of Fig. 20;

Fig. 20 is a transverse sectional view through one of the feeding units showing a portion of the mechanism for feeding the forms. It may be considered as taken in the direction of the arrows substantially along the line 20—20 of Fig. 12;

Fig. 21 is a fractional sectional view taken in a downwardly direction as indicated by the arrows along the line 21—21 of Fig. 12;

Fig. 22 is a fractional transverse sectional view through the machine showing a portion of the mechanism near one end of one of the feeders and may be considered as taken in the direction of the arrows substantially along the line 22—22 of Fig. 13;

Fig. 23 is a longitudinal fractional sectional view taken in the direction of the arrows substantially along the line 23—23 of Fig. 22;

Fig. 24 shows the mechanism of Fig. 22 in an alternative position;

Fig. 25 is a longitudinal fractional sectional view taken in the direction indicated by the arrows along the line 25—25 of Fig. 24;

Fig. 26 is a vertical transverse sectional view showing a detail of the feeder mechanism and may be considered as taken in the direction of the arrows along the line 26—26 of Fig. 13;

Fig. 27 is similar to Fig. 26 excepting that it shows the mechanism in an alternative position;

Fig. 28 is a detail view showing an air valve incorporated in a feeding unit and may be considered as a vertical transverse sectional view taken in the direction of the arrows along the line 28—28 of Fig. 13;

Fig. 29 is similar to Fig. 28 excepting that it shows the valve mechanism in an alternative position;

Fig. 30 is a fractional vertical transverse sectional view taken in the direction of the arrows along the line 30—30 of Fig. 12. This shows the valve mechanism of Fig. 29 from the opposite side;

Fig. 31 is a side view, partially broken into section, of the valve mechanism of Figs. 28 and 29 and may be considered as taken in the direction of the arrows along the line 31—31 of Fig. 28;

Fig. 32 is a fractional plan view of a portion of the caliper mechanism for detecting faulty forms and is taken in the direction of the arrows along the line 32—32 of Fig. 12;

Fig. 33 is a fractional view drawn to larger scale show-

ing a portion of the mechanism of Fig. 32 so as to illustrate further the details of construction;

Fig. 34 is a sectional view that may be considered as taken horizontally in the direction of the arrows along the line 34—34 of Fig. 33;

Fig. 35 is a fractional view showing a portion of the mechanism for picking up and delivering an individual form. It may be considered as taken downwardly in the direction of the arrows substantially along the line 35—35 of Fig. 12;

Fig. 36 is a sectional view in a vertical plane taken through one of the sucker heads as indicated by the arrows along the line 36—36 of Fig. 35;

Fig. 37 is a detail view taken in a vertical transverse plane in the direction of the arrows along the line 37—37 of Fig. 12;

Fig. 38 is a fractional vertical longitudinal sectional view of a detail of the caliper mechanism and may be considered as taken in the direction of the arrows along the line 38—38 of Fig. 15;

Fig. 39 is an end view of the structure shown in Fig. 38 and may be considered as taken in the direction of the arrows along the line 39—39 of Fig. 38;

Fig. 40 is a view of the mechanism of Fig. 38 from the other end and may be considered as taken in the direction of the arrows along the line 40—40 of Fig. 38;

Fig. 41 is a vertical transverse sectional view through a portion of the hopper mechanism and may be considered as taken in the direction of the arrows along the line 41—41 of Fig. 13;

Fig. 42 is a fractional view taken on an oblique plane looking generally upwardly as indicated by the arrows along the line 42—42 of Fig. 41;

Fig. 43 is a detail vertical transverse sectional view showing a portion of the hopper mechanism from the side and may be considered as taken in the direction of the arrows along the line 43—43 of Fig. 13;

Fig. 44 is a similar view but taken along the line 44—44 of Fig. 13;

Fig. 45 is a view similar to Figs. 43 and 44 but taken along the line 45—45 of Fig. 13;

Fig. 46 is a view from the upper end of the structure of Fig. 43 and may be considered as taken in the direction of arrows 46—46 of that figure;

Fig. 47 is a similar view of the upper end of the structure of Fig. 44 and is taken in the direction of the arrows along the line 47—47 of Fig. 44;

Fig. 48 is a similar view but taken in the direction of the arrows along the line 48—48 of Fig. 45;

Fig. 49 is a vertical transverse sectional view through a feeder showing a portion of the form pickup mechanism and may be considered as taken in the direction of the arrows along the line 49—49 of Fig. 35;

Fig. 50 is a view similar to Fig. 49 but showing the structure in an alternative position;

Fig. 51 is a view looking obliquely downwardly at a portion of the hopper mechanism and may be considered as taken in the direction of the arrows along the line 51—51 of Fig. 14;

Fig. 52 is a sectional view at right angles to that of Fig. 51 and is taken in the direction of the arrows along the line 52—52 of Fig. 51;

Fig. 53 is a view similar to Fig. 52 but showing the structure in an alternative position; and

Fig. 54 is a sectional view taken in the direction of the arrows substantially along the line 54—54 of Fig. 51.

The detail views illustrating the feeder frequently omit many of the parts for purposes of simplicity and clarity. The figures are drawn to show in each of them the co-operating elements which carry out successive feeder operations.

By referring primarily to Figure 1, it will be seen that the feeding and gathering machine is composed primarily of the feeders, indicated generally by the numeral 69, and the gatherer, indicated generally at 62. Both of these

structures are supported upon a base 64 built up of a plurality of generally rectangular iron castings 66 in parallel side-by-side relationship. Each of these castings extends generally from front to back of the machine and has semi-cylindrical horizontal recesses in its upper surface fitted to parallel longitudinally extending bars 68, 70, 72 and 74. These bars extend from end to end of the machine and are secured to each of the castings 66 by caps 76. Preferably the individual base members 66 are secured to the floor of the room in which the machine is housed by expansion bolts, lag screws or studs cast into the floor. The base therefore is very rigid and well able to maintain alignment of the machine elements.

Each of the caps 76 has a socket in its upper surface for securing to vertically extending rods 78, 80, 82 and 84. These rods act as pedestals which support the various elements of the feeder and gatherer in proper spaced relationship.

The rods or posts 84, which may be considered as being located at the front or loading side of the machine, support elements at their upper ends which form a jogging table 86. This table is simply a stand which provides a horizontal surface 88 in front of the loader or box filler. It also has a comparatively short vertical surface 90 at the side away from the loader so that a stack of forms may be shaken into better alignment with each other before they are placed in the hopper of the machine, the hopper being indicated generally at 92. The pair of posts 82 and 80 next in position away from the loader are clamped at their upper ends by fittings 93 to longitudinally extending bars 94 and 96 which in turn support and keep in alignment the elements of the feeders and a portion of the gathering mechanism. In order to provide additional rigidity, these horizontal rods 82 and 80 are tied together in the fore and aft direction by upper and lower tie rods 98 and 100 secured at their ends in fittings 102 which are clamped to the posts 80 and 82. In addition at least some of the upper fittings, attached to the forwardmost ends of the upper tie bars 98, also are secured to tie bars 104 which similarly are clamped by fittings 106 to the forward vertical posts 84. Also, the lower rearward fittings 102 are secured to other tie rods 108 clamped by fittings 110 to the posts 78 which support the principal portion of the gathering mechanism. Preferably all of the fittings 102, 106 and 110 are secured directly and securely to the tie rod ends and have removable caps by means of which they are clamped to the vertical posts. Thus, if desired, any of the rods can be removed from the machine without requiring substantial disassembly as would be necessary if the mechanism had to be cleared from either the top or bottom ends of the posts before the fittings 102, 106 and 110 could be slid off and removed.

The horizontal upper bars 94 and 96 are clamped at intervals by caps 112 to bracket fittings 114 and 116 which in turn are bolted to and support parallel vertical transversely disposed generally rectangular end plates 118. The vertical plates 118 are spaced apart so that in general the mechanism comprising one feeder is located between each pair of adjacent plates. In other words these plates 118 may be considered as end plates for the individual feeders, each of the plates, of course, supporting the left hand portion of one feeder mechanism at one side and the right hand portion of the adjacent feeder at the other side. The two plates 118 at the ends of the machine, of course, carry the mechanism at only one side of the end feeders. There are therefore one more of the plates 118 than there are feeders in the feeding mechanism.

The main drive shaft of the machine, which is indicated at 120, extends longitudinally through bearing boxes 122 which are formed in brackets 124 clamped at their ends to the transverse tie rods 98 and 100 so that the drive shaft is in a position somewhat forward of the vertical center line of the feeding mechanism and well below the

end plates 118. Power therefore may be taken off from this shaft to the feeders by means of vertical shafts 126 at appropriate intervals. These vertical shafts (there are about one to each twelve to sixteen feeders) are journaled in bearings 128 provided in brackets 130 clamped to the vertical frame posts 82 at a position between the upper tie rods 98 and the lower edges of the unit end plates 118. At its lower end each shaft 126 carries a crown bevel gear 132 which meshes with a pinion 134 of smaller pitch diameter secured to rotate with the drive shaft 120. This enables the drive shaft to be driven at a higher speed than the power take-off shaft 126 so as to reduce the torque in the long shaft 120, thereby promoting better synchronization between the individual feeders. At its upper end each shaft 126 carries a pinion 136 meshed to a larger crown bevel gear 138 secured to drive a horizontally extending feeder cam shaft 140. Each of the cam shafts 140 extends through several feeders and revolves at a considerably lower speed than the main drive shaft 120. Because of the fact that the shafts 140 are driven from the high speed shaft 120, the considerable torque reaction upon the shafts 140 does not cause the angular lag from feeder to feeder as would otherwise be the case were it attempted to drive all of the feeders directly from a single continuous shaft 140 simply by supplying power at one point.

A second power take-off from the main drive shaft 120 is provided by the sprocket and chain drive combinations comprising a driven sprocket 141, a chain 142 and driving sprockets 143 the latter being keyed or mounted to rotate with the drive shaft 120. The driven sprocket 141 is bolted to a hub 145 which floats or rotates freely on the cam shaft 140. The sprocket and chain drives are used to drive the feed rolls as will be explained in detail hereinafter, and there usually will be a single sprocket and chain drive for each twelve to sixteen feeders. The feed rolls are driven to deliver the forms of the gatherer at a rate determined by whether the whole unit is being operated "one up" or "two up," i. e., whether adjacent feeders deliver different forms or whether the feeders of adjacent pairs deliver the same forms. The feed roll shafts are driven two or three times as fast as the cam shaft 140, and different sizes of driving sprockets 143 are provided to make the necessary adjustment in the feed roll speeds. Any variation in speed in the cam shaft 140 is obtained by varying the speed of the drive shaft 120.

Each of the vertical posts 80 also supports upper and lower brackets 144 and 146 which position tracks 148 and 149 for an endless conveyor chain 151 in a manner to be described in greater detail subsequently. At this point it is sufficient to point out that the conveyor chain 151 is also driven by the main power shaft 120 so that its movement will be synchronized with that of the individual feeders. This conveyor chain comprises one of the essential elements of the gatherer. The particular drive mechanism for the chain is not shown since it is conventional in construction and may comprise any suitable sprocket and chain or gear drive arrangement, its purpose being, of course, merely to drive the chain 151 at a rate of speed, which is a function of the speed of rotation of the shaft 120 so that the incremental longitudinal movement of the chain with each rotation of the shaft 120 is constant and is sufficient to advance a point on the chain from one feeder to the next with each revolution of the shaft 140, one printed form, as will be explained later, being ejected into the gatherer by each feeder upon one revolution of the cam shaft 140.

A stack of forms, after they have been loosened up and aligned on the jogging table 86, are placed by the loader in the hopper 92. By referring particularly to Figure 14, where the general layout of the hopper is well illustrated, it will be seen that the forms are placed in a generally V-shaped receptacle one face of which is made up of a pair of articulated plates 152 and 154. These plates together provide a slightly concave smooth surface

against which the operator places the face of the bottom-most in the stack of forms with the edges or spines of the forms resting against two or more parallel rails, indicated at 156. The angle between the lowermost plate 152 and rails 156 is approximately 90° although the angular relationship is adjustable as will appear presently to adapt the machine to a variety of conditions which arise during operation. The lowermost edge of the plate 152 is positioned a considerable distance above the lower ends of the rails 156 so that, although the flat face of the stack of forms is supported over the major portion of its area by the plates 152 and 154, a considerable portion of the bottom form at the spine is exposed below the lower plate 152 although the spines of all the forms are supported by the rails 156. The forms therefore cannot of their own accord fall downwardly through the slot between the lower edge of the plate 152 and the lower ends of the rails 156.

Referring more particularly to Figs. 41 and 42, where a portion of one of the end plates 118 appears, it will be seen that the group of rails, indicated generally at 92, is carried ultimately by a flat steel plate 158, one end of which is pivoted to the end plate 152 by a bolt at 160. This plate lies at an angle of approximately 45° and is inclined upwardly from this pivoting point. Toward the other end of the plate a latch pin 162 fits loosely in a hole 165 drilled through the plate 158 and is urged toward the end plate 118 and into a hole 166 therein by a leaf spring 164. As the rail support plate 158 is pivoted about the bolt 160, the end of the pin 162 therefore describes an arc where it presses against the end member 118. A plurality of these holes 166 of a size which the pin 162 can enter are drilled through the end plate 118 along this arc so that the pin 162 can be pulled outwardly until it clears the face of the plate 118, whereupon the plate 158 may be pivoted to any of a number of positions at which the pin 162 will snap into one of the openings 166 and retain the rail support plate 158 in place for a trial run. Also, a bolt 167 may pass through the end plate 118 and through an arcuate slot 169 in the support plate 158 at a point removed from the pivot 160. This may be tightened to lock the support plate 158 after it has been properly adjusted. One of these support plates is provided at each end of each unit and they in turn are connected to a pair of longitudinally extending rods 168 and 170 which are in parallel relationship with their surfaces tangent to a plane having an angularity of approximately 45° when the pins 162 are in certain of the holes 166. These parallel cross rods 168 and 170 support the rails 92 and the associated mechanism, all of which is simply clamped thereto in a readily removable and adjustable manner so that the hopper may be easily set up to fit a stack of forms of the desired size.

To set up the hopper to take a load of a certain size, a pair of stack side guides 172, shown in Figure 43, are attached to the rods 168 and 170 at each side and are spaced apart an appropriate distance to take the forms slightly loosely therebetween. They are each composed of a generally angular support bar 174 which has a pair of parallel semi-circular grooves in the lower edge thereof of proper size and properly spaced to fit over the rods 168 and 170. The bar 174 is held to these rods by a pair of clamps made up of a strip or clip 176 which bears against the opposite face of the bar 168 or 170 and is clamped tightly in place by a wing nut 178 threaded to a stud 180, the other end of which is secured in the bar 174. Thus by loosening the wing nuts 178 and pivoting the strips 176 to a position at approximately right angles to that shown in Fig. 43, the support bar 174 may be easily removed from the rods 168 and 170. Similarly it may be placed in position, the strips 176 may be swung in place and it may be slid endwise upon the support rods until properly located, after which tightening the wing nuts 178 quickly secures the assembly in position until it is purposely removed.

The bar 174 carries a pair of support studs or posts 182 on the surface opposite that which engages the bars 168 and 170 and these posts extend upwardly for a matter of an inch or so and there carry a stack side guide bar 184 which is arranged generally parallel to the support bar 174. Thus if a group of forms are placed in the hopper with their spines in approximately the plane defined by the upper surface of the bar 174, they will be prevented from moving from side to side by the stack side guides 172.

When the forms are quickly pulled from the hopper in a manner to be described presently, there are occasions when it is necessary in order to achieve smooth operation to retard the two lower corners of the form being withdrawn in order to prevent its buckling. This result is accomplished by a pair of corner retarders which may be swung into position when their use is indicated. In Figs. 43 and 46 one of these corner retarders is shown at 186. It comprises a generally L-shaped round steel rod, one end of which is inserted into a hole drilled lengthwise into the lower end of the side guide bar 184, it being held in place by a locking pin 188 which is threaded into an opening intersecting the drilled hole into which the corner retarder is inserted. The locking pin, which is therefore of the nature of a set screw, is shown as being a small L-shaped rod one end of which is threaded, the other end, inasmuch as it is bent over, may be easily grasped and rotated. Thus, the corner retarder may be rotated and moved longitudinally to the proper position where it is retained by tightening the locking pin.

The edges of the stack also may be supported if it is desirable by a stack retarding screw 190 best shown in Figs. 41, 42, 43 and 46. This stack retarding screw is threaded transversely through the end of a headed pin 192 which extends into a second opening drilled longitudinally into the lower end of the bar 184 so that the stem of the pin 192 is generally parallel to the stem of the corner retarder 186. This stem 192 is similarly retained by a second locking pin 194. Thus this locking pin may be loosened to permit the headed pin 192 to be drawn outwardly or pushed inwardly until it is in proper position, after which it is anchored by tightening the locking pin 194. The screws 190 may then be adjusted inwardly or outwardly so as to place its head in proper position to engage the face of the forms at their edges by a desired amount. Although these accessory elements are provided, it will be appreciated that they are not necessarily used on all forms passing through the machine. Their use is highly desirable, however, when difficulty is encountered because of some unusual characteristic of the forms. In other words, long thin forms act differently than short wide ones, and similarly the thickness, pliability and surface characteristics of the paper being fed make it highly advisable to have adjustable features of this general character to adapt the machine to a particular job. This is especially so since it is intended that the machine of the present invention will be run at extremely high speed under which conditions minor differences in the handling of the paper make considerable difference in whether or not there are frequent work stoppages because of malfunctioning.

The spines of the forms are actually supported by two or more rails 196, two being shown, the number actually used, of course, depending upon the size of the forms being fed. These rails which are shown in detail in Fig. 45 are generally rectangular, much like the bar 174 excepting that they are longer and deeper from front to back. Similarly also their lower edge is shaped to provide a pair of semi-circular openings toward the lower end which embrace the rods 168 and 170. Each bar 196 is retained to these rods by clamps which may be considered as identical to those used in the device of Fig. 43 and the same numerals have therefore been used as indicia.

A stack follow-up guide bar 198 is located at the center 75 of the hopper. It is essentially similar to the bar 196

excepting that it is somewhat longer and thinner from front to back so that, although it is also secured to the rods 168 and 170 in the same manner as the bars 196 and 174, its upper face does not quite touch the spines of the forms which lie over it. Preferably it should be made somewhat thicker than the guide bars 196. This bar 198 is milled longitudinally on each side to provide a T slot 200 which serves to guide a stack follow-up weight 202 well illustrated in Figs. 51 to 54.

The follower 202 is made up of a generally rectangular platelike member 204 which may be formed as a casting and which has a width slightly less than the minimum spacing to be used between the rails 196. It is relatively thin so that when it is disposed above the guide rail 198, its top surface is slightly below the upper surfaces of the supporting rails 196. At each side its lower surface is formed to provide downwardly extending parallel ribs 206 which extend longitudinally, thereby providing a slot between them having a width considerably greater than the side to side thickness of the guide rail 198. Although these ribs extend downwardly a considerable distance, they should not have sufficient depth to interfere with the tie rods 168 and 170, except that they are provided with stop hoods 207 engageable with the rod 168 to prevent the follower 202 from running off the inner end of the rail 198. Toward its upper end a pair of transverse pins 208 extend inwardly from the adjacent faces of the ribs 206 and carry spacing rails 210 which fill up the major portion of the space between the ribs 206 and the guide rail 198. These pins loosely fit either the rails or the ribs so that the casing 204 is pivoted relatively to the rails. At their inner ends the pins 208 are headed and journal rollers 212 which closely fit and ride in the T slot 200. At a point somewhat farther down the follower toward its bottom end a similar set of rollers 212 are carried upon transverse pins 214 secured near the other ends of the spacing rails 210. Instead of being pivoted at each end in the downwardly extending ribs 206, however, the ribs at this point are drilled to provide a considerably larger hole or cutaway portion 216 as best seen in Fig. 54. The result is that the follower as a whole is free to slide up and down, guided by the T slot in the rail 198. Also since the major portion of the follower is pivoted to the pins 208, its opposite end is free to rock up and down because of the looseness provided at the holes or cutaway portions 216. Near the holes 216 each of the rails 210 has a cavity 218 in its upper surface to house a coil spring 220, the upper end of which bears against the lower surface of the follower plate 204, and urges it upwardly so that the nose or lower end 222 of the follower plate rises to a level somewhat above the top surfaces of the form supporting rails 196.

This device functions in the following manner. Normally it will be in the position shown in Fig. 53 with the nose 222 above the level of the rails 196. It therefore bears against the stack of forms near their spine and because of its weight urges them downwardly into the feeding mechanism. When an additional stack of forms is to be added to those already in the hopper, it is necessary merely to lay them on top of the forms already in place. Because of their weight they will urge the lower portion of the plate 204 downwardly thereby compressing the springs 220 somewhat. After they are properly positioned, the loader grasps the upper end of the follower plate 202 and pulls it upwardly along the rail 198. Because of the weight of the forms, the nose 222 will remain depressed so that it is flush with the spines of the forms, in other words, flush with the top surfaces of the rails 196 until it has been pulled from beneath the last of the forms. As soon as the nose 222 emerges, it immediately snaps upwardly and the follower may be released by the operator. It thereupon slides down the rail 198 and comes to rest with

the nose 222 against the uppermost form in the stack, thereby carrying the forms downwardly to the feeding mechanism. By the use of this device an additional pile of forms may be placed in the stack to retain those already in place before the follower is moved into the new position. Also it is not necessary for the loader at any time to remove the follower completely from the guide rail, it being merely pulled upwardly enough to clear the uppermost form in the stack. On the other hand, if for some particular reason the follower is not needed, because of the nature of the particular forms being fed into the machine, it is easy simply to pull it upwardly off the end of the guide rail 198 and lay it aside.

Sometimes there is difficulty in separating the bottom-most form in the stack from the one in contact with it in order to permit withdrawal of the lowermost form by the mechanism to be described presently. I therefore provide a means for slightly disturbing the contact between these two forms by directing a jet of air upwardly at the spines at the position of the lowermost form. In the present embodiment of the invention this arrangement is comprised of a drilled passage which extends upwardly through the lower end of the central guide rail 198 and is connected to a blower tube 224 best shown in Figs. 44 and 52. This blower tube may be connected to a length of rubber tubing leading to a source of air under pressure.

It is also advisable to use a thin knife blade 223 engaging the spine of the bottommost form at about the center thereof for a slight distance to buckle this form slightly as it is withdrawn from the stack. This buckling action coupled with the air stream effectively separates the form being removed from the second form in the stack. The type and sharpness of the knife blade as well as its height above the rail 198 is dictated by the type and thickness of the form to be fed. For single sheet forms a sharp hooked knife blade is frequently used, while a duller rounded one is used with heavier forms. It will be appreciated that a sharp knife blade 223 will notch the form as it is withdrawn from the stack, but this notching does not interfere with any further operations of the feeder. The knife blade is adjustably slidably in a slot 226 extending from front to back through the end of the guide rail 198, and is locked in its adjusted position by a pair of screws 228.

Further control over the removal of the forms from the hopper is obtained by pins 227 adjustably secured by set screws 229 in the inner ends of the rails 196. These pins exert a slight retarding action on the form being removed which aids in its buckling and separation from the second form in the stack.

It has previously been mentioned that the two hopper back plates 154 and 152 are disposed in approximate alignment and between them form a slightly concave surface which is at about 90° to the guide rails at the other side of the hopper. Of these two plates the uppermost is somewhat the smaller and remains stationary although its position is adjustable. It is provided on its back surface with ears 230 which are secured by bolts 232 to the ends of offset brackets 234 clamped to a cross bar 236. This bar extends from side to side of the machine and is anchored at its ends in brackets 238 bolted to the frame side members 118 so that the cross bar 236 is in a position somewhat above and to the rear of the rear upper corners of the end plates 118. By loosening the bolts 232 and by loosening the clamping screws which secure the brackets 234 to the cross bar 236, the angularity and fore and aft position of the plate 154 can be adjusted as desired.

The lower plate 152 is similarly provided on its back surface with ears 240 near its upper edge, these ears in turn being clamped by bolts 242 to bracket members 244 which may be considered as similar to the bracket members 234. These members 244 are in turn clamped to

a transversely extending shaft 246 which, instead of being anchored at its ends as is the shaft 236, is journaled for rotation in bearing boxes 248 which in the present instance are formed as a portion of the same fittings 238 that support the ends of the bar 236. Thus with any certain position of the shaft 236, by loosening the bolts 242 and the clamping screws which secure the fittings 244 to the shaft 246, the fore and aft and angular position of the plate 152 can be set. The construction and orientation of the supporting structure for these two plates is well shown in Figure 37.

Near the end of the shaft 246 in a position just inside one of the end plates 118, the shaft 246 is clamped to an oscillating arm 250 well shown in Figures 49 and 50, its position being indicated in dotted lines in Fig. 14. At its end remote from the shaft 246 this arm has a transverse pin 252 therethrough which journals a cam following roller 254. This roller rests upon the face of a cam 256 which is pivoted about a bolt 258 secured in the end plate 118 and has another portion of its edge cut to provide a gear sector 260. This cam element also has a generally rearwardly extending arm 262 clamped to a transversely extending tube 264 which passes through two or more units of the machine where it is supported at additional points by additional arms 262, an arcuate slot 266 being provided in the end plates 118 to permit its free oscillatory movement.

The teeth 260 of the gear sector are engaged by a similar set of teeth 268 which form a gear sector at the end of an arm 270; a cap 274 bolted to the arm 270 forms a bearing therewith by means of which the assembly is journaled on a fixed shaft or bar 272. This shaft 272 extends transversely through the machine and is mounted in a manner to be described in a position somewhat above and behind the main cam shaft 140 which extends through the feeder. A cam following arm 276 extends forward in a position above the cam shaft 140 and carries a roller 278 at its end. This roller engages the surface of a disc shaped cam 280 which is secured to and rotates with the cam shaft 140. The cam 280 is cut so that as the shaft 140 rotates, the roller 278 will be raised and lowered somewhat and therefore will rock the arm 270 about the shaft 272. In order to insure that the roller 278 will follow the surface of the cam 280 inwardly toward the center of rotation at 140, as well as outwardly, the cap 274 also has an armlike extension 282 which carries a second cam following roller 284 which engages the surface of a second cam 286 also secured to the cam shaft 140. This second cam 286 is so cut that as the cam 280 moves the roller 278 away from the center of rotation at 140, the second cam 286 permits the roller 284 to move in toward the center of rotation. Conversely as the surface of the cam 280 moves away from the roller 278, the cam 286 at this point forces the roller 284 outwardly thereby insuring that both rollers will follow their cams closely at all points during the cycle.

From the above it will be seen that as the cam shaft 140 rotates, the arm 270 will oscillate and this in turn will cause oscillation of the transversely extending suction tube 264 and because of the oscillatory movement of the cam 256, its follower 254 will cause oscillatory movement of the rock shaft 246, which in turn causes the lower hopper plate 152 to swing inwardly and outwardly slightly at its bottom edge during each cycle of the machine. Although the timing of the several oscillatory and other cyclical movements will be discussed subsequently, it should be noted at this point that the cams 280 and 286 are cut to give the tube 264 the proper movement and that cam 256 is so shaped as to translate this movement into what is desirable so far as movement of the hopper plate 152 is concerned, these two movements occurring simultaneously but not being the same.

Two or more suction heads, indicated generally by the numeral 288, are arranged to pull the spine of the lower-

most form away from the ends of the supporting rails 126 and into the slot formed generally between the ends of these rails and the bottom plate 152 of the hopper. Each of the suction heads 288 is made of a fitting 290 which is clamped about the tube 264, a tube 292 being secured in the fitting and extending obliquely downwardly and forwardly to support the sucker head 294. A passage is drilled through the fitting 290 and through the tube 264 in alignment with the extension tube 290 to form a passage 296 which is transversely intersected by a needle valve 298 which may be adjusted with a screwdriver to give the desired restriction to flow through the tube 292. This adjustment is an aid in setting up the machine for a particular job so that the suckers 294 will operate efficiently in extracting only one form from the stack in the hopper. The sucker head 294 is formed preferably as a casting having a shallow circular recess 300 in one face. It is also drilled concentrically with this recess to take the stem 302 of a retainer for a suction washer 304. This washer is formed of soft rubber and is disposed in the recess 300. Its purpose, of course, is to form a reasonably good seal with the lowermost form in the stack and to adhere thereto due to the suction effect produced in the tube 292. In order to promote easy maintenance, these suction washers are secured to the ends of the hollow stems 302, the stem being retained in the head by a set screw 306.

As shown in Fig. 35, two of these suction heads are formed in one casting and are arranged close together at the center of the hopper. Under some conditions the use of more of these heads may be desirable if the forms being handled are particularly long. Once each cycle, as has been explained, the tube 264 oscillates arcuately downwardly and forwardly and then returns to its original position. As it does so it carries the suction heads from the position shown in Figure 49 to that of Figure 50 and return. As will be explained subsequently, at about the time the heads have been carried to the position of Fig. 50, that is in contact with the face of the form which is bottommost in the pile at a point near the spine, the suction line 264 is evacuated so as to cause the form to cling to the heads 294. As these heads swing backwardly and downwardly to the position of Fig. 49, they therefore withdraw the spine edge of the lowermost form from the pile and into a position where it can be grasped between a set of feed rolls 308 and pinch rolls 310 which cooperate therewith and which are spaced apart so as to straddle the suction heads.

The feed rolls are fixed upon a rotatable shaft 312 which extends longitudinally through the machine and is journaled in bearing boxes fixed to the end plates 118. If desired this feed roll shaft may extend through several units and at some point is driven by a gear train well shown in Figs. 1, 12 and 16 where it will be seen that the cam shaft 140 carries a floating pinion 314 formed on or secured to the hub 145 of the sprocket 141. This pinion drives a larger gear 316 meshed therewith. This larger gear is carried upon a short axle 318 to which is secured at one end a vertically extending arm 320 which supports one end of the shaft or bar 272. The bar 272 extends through the feeder and is supported at its opposite end in the plate 118. This cross bar supports additional equipment to be mentioned presently but for the moment it may be considered as simply a fixed bar or rod which is positioned somewhat above and behind the cam shaft 140. The intermediate gear 316 in turn drives a pinion 324 mounted upon a caliper roll shaft 326. The primary function of this shaft will appear presently, it being journaled at its ends in bearing boxes secured to the end plate 118 in a position somewhat above and behind the axis of rotation of the intermediate gear 316. If desired, it may extend through several units or if preferred may be individual to each unit. The drive in turn is transferred from the caliper roll pinion 324 to an intermediate idler gear 328 which in turn is

meshed with and drives the feed roll drive shaft gear 330 which is fixed to the shaft 312 upon which the feed rolls 308 are mounted. Incidentally the feed roll shaft 312 also carries a larger gear 332 meshed with a pinion 334 mounted upon a short stub shaft carried in bearing boxes 336 secured to the end plate 118. By means of this gear train the feed rolls 308 are driven continuously in a clockwise direction as seen in Figs. 14, 20 and 26.

The pinch rolls 310, which co-act with the feed rolls 308, are somewhat smaller in diameter and are located slightly below the plane of the hopper support bars 196. They are fixed to rotate with a short shaft 338 which is carried at the end of a bracket 340 pivoted in turn at its other end to the previously mentioned cross shaft 272. As best shown in Figs. 26 and 27, the bracket 340 is hinged at its center so as to be flexible. That is, the end carrying the short shaft 338 with the rolls 310 is pivoted to a pin 342 which extends transversely through the lower half of the bracket 340. This lower half has a forwardly offset arm 344 which carries a cam following roll 346 journaled upon a short cross shaft 348. This cross shaft also has an enlargement 350 which is drilled transversely to pass a guide pin 352 which is threaded at its lower end to take an adjusting nut and lock nut 354 while its upper end is pivoted to a pin 356 secured in the upper half of the bracket 340. A coil spring 358 surrounds the portion of the guide pin 352 between the shaft 348 and the pivot pin 356 with the result that if it is assumed that the cam following roll 346 is maintained in any certain position, the spring 358 will tend to swing the upper half of the bracket upwardly and rearwardly so as to move the pinch rolls 310 toward the feed rolls 308. Movement in this direction is limited by the setting of the adjusting and lock nuts 354 threaded to the lower end of the pin 352.

The cam following roller 346 rests upon the edge of a disc cam 360 carried by the cam shaft 140 and adapted to raise the cam following roller 346 during a portion of each cycle of the machine. The roller 346 is maintained in contact with the cam 360 by a fitting 362 pivoted to the end of a lower arm extension 364 formed as a portion of the lower half of the bracket 340. The fitting 362 is connected to a guide pin 366 which extends generally forwardly with its opposite end passing through and arranged to slide in a guide block 368 clamped to a longitudinally extending support bar 370 anchored at its ends in the end plate 118. The portion of the guide pin 366 between the guide block 368 and the fitting 362 is surrounded by a coil spring 372. Thus throughout the cycle of operation the coil spring 372 will urge the bracket 340 in a clockwise direction around the support bar 322 so as to keep the cam following roller 346 always in contact with the cam 360. The portion of the cam 360 farthest from the center of rotation at the shaft 140, when in contact with the cam following roller 346, will slightly more than bring the pinch rolls 310 into contact with the feed rolls 308, the excess movement being absorbed by the spring 358. Inasmuch as the pinch rolls 310 oscillate backwardly and forwardly, they are driven by a universal joint arrangement which comprises sockets 374 formed in the ends of the pinch roll shafts 338 in approximate alignment with similar sockets 376 formed in the stub shaft which carries the gear 334. A drive shaft 378 has ball fittings 380 formed at each end which slide within the socket recesses 374 and 376, the drive being transmitted to and from the drive shaft by transverse pins 382 extending through the ball heads and into slots 383 which extend transversely across the sockets 374 and 376. The result is that the gear 334 can rotate on a fixed axis so as to remain meshed with the gear 332 while the pinch rolls are free to oscillate inwardly and outwardly. This universal drive connection need not be present in each unit of the machine, it being appreciated that once the drive has been communicated to the oscillating shaft 338, successive similar shafts in

successive units of the machine for a considerable distance can be continuous since all of the pinch rolls may oscillate inwardly and outwardly together. The pitch diameter of the gear 332 which revolves with the feed rolls 308 should have approximately the same ratio to the pitch diameter of the gear 334 as the diameter of the feed rolls 308 bear to the diameter of the pinch rolls 310 so that both the feed rolls and the pinch rolls will have the same peripheral velocity.

10 The forms pass between the feed rolls and the pinch rolls at high speed and in order to keep control of them as they pass on through the machine, a row of grid members 384 have been provided. As shown, each of these members comprises a casting having a generally 15 smooth slightly concave downwardly extending surface which starts at the elevation of the feed rolls and pinch rolls. The upper portion of each grid member has a comparatively large opening 386 therethrough to allow passage of the oscillating pinch roll drive shaft 378. 20 This permits the pinch roll shaft to be moved backwardly and forwardly with the pinch rolls without interference from the grid members while at the same time permitting the upper ends of the grid members to be at a point high enough to prevent the possibility of the 25 corners of the forms being ejected from being bent over or otherwise getting out of control before receiving support from these grid members. The grid members are drilled crosswise and are slid endwise upon the rod 342 previously referred to as serving to pivot the upper half 30 of the bracket 340 which supports the pinch rolls to the lower half thereof. The grid members are secured to this rod by set screws and of course oscillate with the rod 342. This oscillation, however, does no harm since the degree of movement of this rod 342 is relatively 35 limited. In order to control the forms over substantially the entire path through the machine the lower ends of the grid members are cut away to form yokes 388 indicated in Fig. 20 which straddle the longitudinally extending tie rod 272. The grid members therefore support 40 the form being fed until it has reached a point somewhat past the center line of the bar 272. From this point on support is taken over by a separate set of grid members 390 which are secured to the support bar 272 and extend downwardly and rearwardly as far as necessary. 45 An inner set of grid members 392 is also shown. They extend downwardly from the bar 322 with their lower ends anchored by clips 394 to a longitudinally extending stationary support rod 396 which has one end secured to one of the side plates 118 while at its center it receives support from a caliper support bracket 398, the main function of which will be pointed out 50 presently. This bracket, which is a comparatively massive casting is secured to one of the main longitudinally extending support bars 96.

55 The exact contour of the grid members of course depends to a considerable extent to the exact layout of the elements in the unit, the principal requirement being simply that they provide sufficient support for the lower faces of the forms being passed through the machine so 60 that the corners will not be bent backwardly and torn or folded under. In this connection it should be appreciated that because of the high velocity of the forms through the machine, one of the factors which causes some difficulty unless provision is made to take care of 65 it is the resistance to passage of the forms through the air. In other words, the effect of passing the forms through the air is much like that of a wind blowing in the opposite direction.

From the feed rolls and pinch rolls the forms pass 70 downwardly and rearwardly spine first along the grid members 384 until they arrive tangentially to a second set of feed rolls 400 which supplies a caliper mechanism. This set of feed rolls 400 is mounted upon the longitudinally extending shaft 326 previously referred to. 75 The feed rolls 400 therefore rotate in a clockwise direc-

tion as seen in Fig. 14, or in other words, in the same direction as the feed rolls 308. The form is kept in contact with the feed rolls 400 by a set of rubber idler rolls 402, each of which is carried upon a short transverse shaft 404 at the rearwardly extending end 406 of an arm 408 which extends around the support bar 272 and is pivoted to the grid rod 342. Each rubber roll 402 is held in contact with its feed roll 400 by a coil spring 410 which bears with one end against a fitting 412 pivoted by a pin 414 to the arm 408 while the other end of the spring presses against a guide block 416 clamped to the cross bar 370. The spring and fitting 412 are kept in alignment by a guide pin 418 which slides through a drilled hole in the block 416 and which passes axially through the spring 410 with its opposite end secured in the fitting 412. With this structure it will be seen that the rotating feed rolls 400 with the aid of the rubber friction rolls 402 in contact therewith pick up the forms which have passed downwardly along the grid bars 384 and pass them out of the machine at the lower left edge, the rubber roll 402 always maintaining approximately the same pressure against the feed roll 400 because it is urged into contact therewith or against the back surface of a form by the freely acting spring 410.

Beyond the feed rolls 400 and the idling rolls 402 the forms are passed downwardly and rearwardly over the face of an inclined sheet metal apron 420 until the spine of the form is brought to a stop by the trough, indicated generally by the numeral 422 of the gatherer. The apron 420 has a width greater than the form and supports it in proper position to prevent its buckling when its motion is suddenly arrested. Subsequently when the form is carried forward by the gatherer it slides off the apron and the top portion drops against the smooth surface of an inclined table 424 so as to make room on the apron for the next form in the series.

The caliper roll shaft 326 previously referred to carries a set of closely spaced caliper rolls 426 mounted at its mid-point. Actually these two caliper rolls are formed from a single piece of steel as one wide roll with a groove cut at the center, the purpose of this groove being simply to permit caliperizing of the forms, moving through the feeder on each side of any notch that might be formed at the spine by the knife blade 223 previously referred to. Preferably the caliper roll 426, which rotates with the shaft 326, is driven at such a speed that it makes two or three revolutions with each cycle of operation of the machine. The speed of the caliper roll, it will be observed is the same as that of the feed rolls 308 and 400 and is sufficiently high to insure rapid passing of the form through the feeders. Since the caliper roll speed is a whole number multiple of the operation cycle the effect will be that slight wobbling of the shaft 326 will not have the effect of causing malfunctioning of the caliper mechanism. This is because the in and out movement produced by such wobbling will always occur at the same point in the cycle and therefore is automatically compensated for when the caliper mechanism is adjusted. It will be appreciated, however, that the best practice is to make the caliper rolls with considerable care so that the surface does not wobble appreciably during operation.

A caliper rock shaft 428 is mounted somewhat below and in front of the caliper roll shaft 326, it being journaled at one end in a bearing mounting secured to one of the end plates 118 while its other end is similarly carried in a bearing mounting secured to the bracket 398 previously mentioned. The rock shaft 428 therefore extends longitudinally of the machine and is free to wobble rotationally. In a position in alignment with the caliper rolls 426, the rock shaft 428 carries a gauging roll fork 430, this fork in turn journaling a gauging roll 432 offset from the axis of the rock shaft. The gauging roll has a circular groove 434 of approximately the same width as the groove at the center of

the caliper roll 426. The fork 430 carries the gauging roll 432 in a position somewhat below and in front of the caliper roll 426 and therefore is swung so as to bring the gauging roll into contact with the caliper roll when the rock shaft 428 is rotated in a counterclockwise direction as seen in Fig. 15. Pivotal movement in this direction is resiliently achieved by a coil compression spring 436 which acts between a horizontal platform 437 on the bracket 398 and a fitting 438 pivoted in an off center position to the fork 430, the fitting having a stem 439 which passes through the spring and is guided in a hole 440 in the platform. With this arrangement it will be seen that the gauging roll may be held against the caliper roll by the coil spring 436 unless a form is passing between the drive rolls 400 and the rubber idling rolls 402, and consequently between the caliper rolls 426 and the gauging rolls 432. Whenever a form does pass between the caliper roll and the gauging roll, the gauging roll will, of course, move outwardly slightly depending upon the thickness of the form, thereby rotating the shaft 428 slightly in a clockwise direction as seen in Fig. 15.

This motion is in turn communicated to a two piece bracket fitting 442 secured to the rock shaft 428, the upper end of which is formed to provide a gear sector 444 meshed with a sector 446 of smaller pitch diameter which is formed at the lower end of a caliper segment lever 448. At the pivoting center of the sector 446 the lever 448 is journaled, preferably like the other elements of the machine in anti-friction bearings 450 mounted upon a bolt 452 secured to the end plate 118. The upper end of the segment lever 448 is pivoted by a transverse pin 454 to the forward end of a generally horizontally extending link 456 which comprises the body portion of the caliper.

In order to take any possible back lash out of the system, a coil spring 458 is hooked through a hole near the top end of the lever 448 and extends forwardly and has its opposite end anchored to a pin 460 secured in the end plate 118. Similarly a spring 459 pulls forwardly on the lower end of the bracket 442. Also the pin 452, which carries the bearing 450 at the center of rotation of the sector 446, may be slightly eccentric to the bearing center line so that by rotation of this pin before it is tightly clamped in place by the nut 462, the degree of meshing of the two sectors 444 and 446 may be precisely adjusted.

Furthermore to promote adjustability of the device, the bracket 442, as previously mentioned, is comprised of two principal pieces. One of these carries the sector 444 and is clamped to the shaft 428 by the clamping bolt 466. A bearing 464 is pressed into a recess 465 in the bracket 442 and has its center race secured to the end plate by a bolt 467. The right end of the shaft 428 (Fig. 38) and the bracket 442 are thus pivotally mounted; the left end of the shaft is similarly pivotally mounted through a bearing 469. Locking adjustment of the shaft 428 and bracket 442 is achieved by an arm 468 clamped to the shaft 428 in substantially face to face relationship with the main portion of the bracket 442, there being a cross pin 470 which extends from the arm 468 into a recess 472 formed in the face of the main portion of the bracket 442 at a point just below the sector 444. At this point the bracket is formed to provide a pocket to receive a coil spring 474 which presses against the transverse pin 470 at one side, thereby tending to rotate the sector 444 away from the arm 468 in the direction which permits elongation of this spring. This tendency is resisted by an adjusting screw 476 in alignment with the spring 474 but at the opposite side of the pin 470. Thus simple adjustment of the screw 476 with a screwdriver establishes the desired angular relationship as between the arm 468 which is clamped to the shaft 428 during the adjustment, and the remaining portion of the bracket 442. When this adjustment has been made the bolt 466 is tightened to clamp the main bracket portion to the shaft.

The main portion of the bracket 442 also has a pin 478 in approximate alignment with the pin 470 which

extends through an arcuate slot 480 in the end plate 118. This stop pin operating against the end of the slot 480 limits the movement of the bracket 442 as the shaft 428 is rotated in a counterclockwise direction by the spring 438. Thus by screwdriver adjustment of the screw 476 the starting position of the gauging roller 432 relative to the caliper roll 426 can be determined. Normally this adjustment will be such that the gauging roll does not quite touch the caliper roll but will have a separation somewhat less than the thickness of the forms passing through the machine. The result is that the forms passing between the caliper roll and the gauging roll will cause the gauging roll to move outwardly slightly but not as much as would be the case if these two rolls were in contact. Malfunctioning due to the inertia in the caliper system is therefore held to a minimum. In other words there is less tendency for the caliper mechanism to overshoot or bounce when a form is passed therethrough since its movement can be made very slight if desired.

From the above it will be seen that when the machine is routinely adjusted to caliper the particular forms being passed through the machine, regardless of whatever thickness they may have, the gauging roll 432 will move outwardly slightly when a form passes, thereby causing the shaft 428 and the sector 444 to be rotated slightly in a counterclockwise direction. This in turn causes the cross pin 454 at the upper end of the segment lever 448 to be moved to the right as seen in Fig. 40. Because the pitch diameter of the sector 444 is considerably greater than that of the sector 446 and because of the length of the segment lever 448 which is great as compared with the yoke 430, the actual movement of the pin 454 forwardly and backwardly as a form passes through the caliper mechanism will be considerable and will be of the order of four or five times the actual variation in thickness of the form. The result therefore is that if a form passing through the machine varies in thickness from that to which the machine is set by a matter of only a few thousandths of an inch, the fore and aft movement of the pin 454 will vary by four to five times that amount.

The caliper body 456 is best shown in Figs. 32 to 34 where it will be seen that its outward end, that is the end not fastened to the pin 454, is urged downwardly by a coil spring 482 wrapped around the pin 454 with one end bent outwardly and hooked over the caliper body 456, while its opposite end is hooked under a screw 484 formed as the portion of a collar 486 secured to the pin 454 near its outer end. This caliper body is generally square in cross section and has a drilled hole 488 extending from the outer end almost to the pin 454. It is also slotted horizontally as at 490 from the outward end over the major portion of its length as best seen in Fig. 34, to take a caliper gauge block 492. This gauge block is generally rectangular in plan and is formed to slide in the slots 490 and hole 488 and to extend on each side of the caliper body portion 456. It is urged outwardly away from the pin 454 by a coil spring 494 located in the drilled passage 488 on the side of the gauge block toward the pin 454. This outward motion is resisted by an adjusting screw 496 having a knurled head 498 which is threaded into the end of the caliper body so that the end of the adjusting screw bears against the end of the gauge block. A locking thumb screw 500 also is threaded to the adjusting screw 496 and has a conical recess in its face which engages a complementarily tapered end of the caliper body. Thus by loosening the locking nut 500 and adjusting the thumb screw 496 the gauge block 492 can be moved inwardly and outwardly as desired with great precision. Once it is properly located, it can be locked in this position by tightening the locking nut 500.

A bracket 502 formed on a bearing boss 503 is carried on the frame end plate 118 near its rearward edge,

the bracket having a vertical face at right angles to the end to which a caliper blade 504 is pivoted at 512. This caliper blade is so supported and guided in a guide 505 secured to the edge of the plate 118 that it may be swung upwardly and downwardly with its free end arranged to pass through a slot or notch 506 formed in the side of the gauge block 492. This slot has a width which is a few thousandths of an inch more than the thickness of the caliper blade so that when the slot is properly aligned with the blade, upward and downward movement of the blade can take place without disturbing the gauge block. On the other hand if the caliper body 456 is moved either inwardly or outwardly slightly with respect to this position, the caliper blade when moved upwardly will catch beneath the gauge block at one side or the other of the slot and lift the gauge block and hence the outer end of the caliper body 456 along with it.

At its outer end the caliper body 456 is supported for free sliding movement on a ball bearing 510 held between 20 a pair of tubular spacers 508 which engage the inner race of the bearing. A pair of side guides 509, one held against the plate 118, are arranged at the outer ends of the spacers with enough clearance therebetween to pass the gauge block 492; these side guides restrain the caliper body 456 against side to side movement. The ball bearing 510, spacers 508, and side guides 509 are locked in position by a bolt 511 extending therethrough and threaded into the bearing boss 503.

The caliper blade at a mid-point is pivoted by a threaded pin 514 to a link 516. This link, as best shown in Fig. 15, extends substantially vertically and has its upper end pivoted as at 518 to the end of a crank arm 520 clamped to a caliper actuating rock shaft 522. The shaft is journaled at its ends in bearings secured to the end plates 118 and carries a second crank arm 524 which extends downwardly therefrom with its lower end pivoted by a pin 526 to a forwardly extending link 528 pivoted in turn by a pin 530 to the upper end of a caliper actuating arm 532. This arm extends downwardly and is clamped by a lower cap member 534 about a bearing mounted upon the cross bar 272 previously mentioned. Incidentally the arm 532 and the lower cap member 534 which is essentially a part thereof can be identical to the rocking arm 270 which actuates the sucker heads. In the case of the latter arm, however, the upper end is cut to form a gear sector, whereas the same casting may be used for the present purpose of actuating the caliper mechanism without need of the sector teeth and the casting with the upper end unfinished is so shown in Fig. 15. The lower end of the cap portion 534 is pivoted by a pin 536 to a fitting 538 having a forwardly extending rod 540 which slides through a block 542 clamped to the forward cross bar 370. A spring 544 surrounds the rod 540 and bears with its ends against the block 542 and the fitting 538 and therefore tends to rock the arm 532 in a clockwise direction as seen in Fig. 15. This arm 532 also has a forward extension 546 which journals a cam following roller 548 bearing against the periphery of a disc cam 550 carried by the main cam shaft 140. This cam is generally circular excepting that it has a single lobe which raises the roller 548 momentarily once each revolution. It therefore rocks the upper end of the arm 532 and the link 528 toward the left as seen in Fig. 15 momentarily once each revolution and then returns it to the at rest position. When it does so, the momentary clockwise motion imparted to the rock shaft 522 acting through the crank arm 520 and link 516 lifts the end of the caliper blade 504. If at this moment the slot 506 in the caliper gauge block is aligned with the end of the blade 504, the blade 504 merely passes upwardly into the slot 506 momentarily and then back downwardly away from the same.

The device is adjusted (the adjustment being made by the caliper adjusting screw 498) so that if a form of the proper thickness is passing between the caliper rolls and the gauging rolls, the caliper body 456 will have been

moved outwardly just the right amount so that the caliper blade 504 will move through the slot 506 without touching the gauge block. If on the other hand the form passing between the caliper rolls and the gauging rolls is slightly too thick or too thin, the caliper body will have moved outwardly too much or not enough so that the caliper blade will catch beneath the gauge block at one side or the other of the slot 506, thereby raising the outer end of the caliper body.

A switch housing 552 is carried by the frame end plate 118 in a position above the caliper body and among other things has a push type switch located therein, this switch being of the precision snap type with its actuating plunger 554 extending downwardly out of the housing 552 in a position just above the caliper body 456. Inasmuch as the particular electrical circuit forms no part of the present invention, it will not be necessary to describe it in detail, it sufficing simply to point out that the switch operates when actuated to interrupt the power supply to the motor which drives the feeders and gatherer and acts incidentally to energize a pilot light located beneath a protecting cap 556 at the upper end of the switch housing 552. The circuit is also such that after the power supply to the motor has been so interrupted, the mechanism can be started again by pressing a start button 558 located upon the switch housing 552.

From the above it will be seen that the caliper mechanism normally causes the caliper blade 504 to move upwardly and downwardly through the slot 506 each time a form passes between the caliper roll and gauge roll so long as the form is of the thickness to which the machine is adjusted. If a form fails to pass at the right point in the cycle, or if two forms stick together, or if a form passes which is either too thick or too thin, the gauge block will not be in the proper position so that the slot 506 will provide clearance for the end of the blade 504 and therefore the outer end of the caliper body will be lifted and will press against the switch button 554. This interrupts the power supply to the feeder and gatherer and also acts incidentally to energize the pilot light 556 on the appropriate feeder so that the operator can quickly determine where the trouble exists. After the trouble has been corrected, the machine is restarted by pressing the button 558 at that particular feeder.

It will be found that in order to insure trouble-free operation of the caliper mechanism, more than one gauge block slot 506 will need to be provided if it is intended to feed forms having a wide variety of characteristics. This is because some forms, particularly those composed of thin paper, will need to have the mechanism set up with the slot 506 narrow as compared with the caliper blade 504 because the presence or absence of a single sheet in such a form will cause shifting of the gauge block only a small amount and therefore in order to insure operation in a satisfactory manner, it will be necessary that there not be very great clearance of the caliper blade as it moves upwardly and downwardly in the slot. On the other hand, if the forms are composed of comparatively heavy paper which may vary in thickness through the run by a large amount, a slot of the same width would cause difficulty even though the forms had the proper number of pages. Of course, when a form is composed of thick pages, the amount the gauge block will be shifted when an improper number of pages are passing through the caliper will be great. For such use therefore a gauge block having a comparatively wide slot 506 is satisfactory and is preferred. Since in the embodiment shown the gauge block is rectangular, it may, if desired, be provided with a different width slot 506a on the other side, the two slots being interchanged simply by removing the adjusting screw, pulling out the gauge block, and reinserting it with its position changed end for end.

The machine of the present invention is intended to operate extremely rapidly and it is therefore advisable to use an unusual valve arrangement for controlling the suc-

tion to the suction heads so as to insure the heads clinging to the form at the proper time, and on the other hand insuring their quick release a moment later. The particular valve for accomplishing this is shown in Figs. 28 to 31 where it will be seen that the transversely extending suction tube 264, which has previously been mentioned as extending from end to end of the sections and in fact through several sections, is supported in a pivoted bracket fitting 560. This fitting is clamped to the tube 264 and is pivoted to rock about a stud 562 secured to the end plate 118. It rocks with the motion of the tube 264 and has an upwardly extending arm 564 having an apron 566 extending on either side. The face of this apron is a plane surface and rests against a similar plane surface of a valve housing 568 bolted to the end plate 118. A suction line 570 leading from a vacuum system communicates with a valve chamber 572 in the housing 568, this chamber communicating with the surface of the valve body in contact with the apron 566 so as to form a comparatively large port. As shown in Fig. 28, when the arm 564 and tube 264 are in one position, the port 572 communicates with a similar but smaller port 574 formed in the face of the apron 566 and which communicates by means of intersecting passages 576 and 578 in the filling with a registering opening in the tube 264. Thus with the parts in the position shown in Fig. 28, air is removed from the tube 264 by way of the passages 578 and 576, the ports 574 and 572 and the suction line 570. On the other hand, when the tube 264 is swung to the opposite end of its cycle, the arm 564 will be swung to the right of the position of Fig. 28 and into the position of Fig. 29 so that the ports 574 and 572 are no longer in register. The overhanging portion of the apron 566, however, under these conditions keeps the port 572 closed, whereas a portion of the flat surface on the valve body 568 acts to close the port 574 and maintain the suction effect in the pipe 264 and the suction heads.

In order to break this suction effect rapidly at the appropriate time in the cycle, the tube 264 also is clamped to a second oscillating valve member 580 of ring shape mounted on the other side of the plate 118. This valve member also forms a portion of a rotary valve and has a port 582 which communicates with the tube 264 and opens to a cylindrical bearing surface 583 formed on a stationary but adjustable combination bearing and valve disc 584 having a ventilating slot or port 586 extending therethrough in a position to register with the port 582 when the valve is in one position, normally the position it assumes when the port 574 is out of register with the port 572. As shown, the ring member 580 of this valve oscillates upon the disc 584 which is secured to the plate 118 by the same stud 562 as the oscillating member 560. The bearing and valve disc may be adjusted about the stud 562 by the eccentric 588 precisely to obtain a point at which the ports 586 and 582 register to break the vacuum in the tube 264. The disc 584 is locked in its adjusted position by the locking stud 587 which extends through the arcuate slot 589 in the disc 584.

By referring particularly to Figure 2, it will be seen that the forms ejected from the machine travel at considerable speed down over the apron 420 until the spine edge of the form is brought solidly to rest in the trough 422 of the gatherer.

This trough is made up of a flat steel support plate 600 which extends from end to end of the gatherer and is supported by brackets, indicated generally by the numeral 602 in a manner to be described in greater detail presently. The plate 600 is at an angle which is somewhat more nearly horizontal than the apron 420 and therefore the forms after they pass off the apron 420 on to the pile of forms supported by the table 424 are slightly bowed concavely. This arrangement has the effect of insuring that the device will not malfunction because of a form occasionally passing beneath the plate 600 and additionally the slight concave curvature stiffens the forms and

prevents their buckling as they are rapidly moved in an endwise direction through the machine.

In a position above the supporting plate 600 of the gatherer and at an angle of approximately 60° thereto, there is arranged a second plate 604 which acts as a director for the form. In other words, if the form in being ejected from the feeder is thrown into the trough formed between the plates 600 and 604 in a slightly high position, the spine will impinge against the plate 604 and will be forced downwardly against the other forms in the stack. I have found that an angle of approximately 60° between these two plates has the desirable effect of preventing the forms bouncing when they hit the gatherer. They therefore stack better and cause less difficulty when they subsequently leave the gathering machine and pass to the stitcher where they are bound together.

The forms in the trough 422 are carried in an endwise direction by a plurality of pins 606 which extend outwardly from the conveyor chain 151 previously mentioned. These pins extend at approximately right angles to the plane of the table 424 and pass through the clearance space which is provided between the lower edge of the table 424 and the upper edge of the support plate 600. Essentially these pins 606 are formed as special links of a roller chain 151. This roller chain of the bicycle type slides in a slot 610 formed between a pair of rails 612 which extend lengthwise through the machine and are supported on short posts 614 supplied at intervals and secured to supporting platforms 616 in a rigid manner. These platforms 616 are in turn supported at intervals by rods 618 adjustably clamped to the fittings 144 previously mentioned as being clamped to the columns 80. The roller chain therefore is free to move in an endwise direction along the track formed by the plates 612 and in one direction of movement the track is so positioned that the gathering pins 606 extend upwardly into a position to impinge against the edges of the forms lying in the trough 422, and carry these forms in an endwise direction. The gathering pins 606 are of course so spaced that they will not be in the way of a form sliding down over the apron 420 but will be brought against the edge of the form shortly after it comes to rest in the trough 422. At the end of the gatherer, after the forms have been delivered to the successive machine, normally the stitcher, the conveyor chain returns to the point of beginning by way of the lower similar track 149 in a position well beneath the trough 422. This relationship is well shown in Fig. 2.

The gatherer heads which support the trough 422 at intervals are arranged in vertical telescoping relation to the previously mentioned columns 78. These heads which probably most easily may be formed as castings 620 have an overhanging arm 622 shaped to carry the support plate 600 at the angular relationship previously mentioned. Each arm also has an upwardly and rearwardly inclined bracket plate 624 at right angles to the plate 600 to which brackets 626 are secured at intervals, these brackets in turn supporting the director strip 604 previously referred to.

Preferably the bracket fittings 626 are secured to the bracket plate 624 by bolts 628 passed through elongated slots either in the plate 624 or the bracket 626 so that by loosening these bolts the bracket 626 may be slid upwardly or downwardly slightly along the plate 624 so as to establish the gap between the lower ends of the supporting plate 600 and the director plate 604, it being appreciated of course that as the forms move through the gatherer the thickness of the pile increases and therefore the gap referred to should be greater toward the downstream end of the machine. The plates 604 and 600 although continuous, nevertheless have sufficient flexibility to permit such adjustment.

In order to adapt the machine quickly to handle forms of a great range of sizes, the fitting which carries the

plates 600 and 604 is preferably formed separately, as indicated by the numeral 629, from the overhanging arm 622 and slides in a keyway 608 therein so that it can move inwardly and outwardly relative to the post 78. This inward and outward movement is brought about by a screw shaft 630 which is journaled to rotate in the head 620 with its outward end threaded into complementary threads in the movable slide carrier for the plates 604 and 600. Thus rotation of this shaft in one direction cause the plates 600 and 604 to be moved outwardly whereas rotation in the opposite direction moves these members inwardly.

The casting which forms the head 620 is supported on the column 78 by means of a vertically extending jack-screw 632 which is journaled at its upper end in the head casting 620 and extends downwardly through the column 78, where it is threaded into a stationary nut therein. Thus rotation of this jackscrew in one direction causes the head 620 to rise whereas opposite rotation permits the head to settle and carry the plate 600 and 604 downwardly.

The head 620 is also formed to journal a longitudinal shaft 634 which extends from end to end of the gatherer and is connected at each of the gathering trough supporting heads to a worm gear 636 meshed with a gear 638 secured to the individual jackscrews 632. It is apparent therefore that rotation of the shaft 634 will cause all of the heads to move upwardly or downwardly together, depending upon the direction of rotation of this control shaft. The shaft 634 at each of the heads also carries a spur gear 640 meshed to an idler gear 642 which in turn drives a third spur gear 644 carried upon a shaft 646. This shaft has a worm 648 thereon meshed with a gear 650 secured to the screw shaft 630. With this arrangement any rotation of the shaft 634 which causes the head 620 and the trough 422 to descend also causes the screw shaft 630 to rotate in such direction as to move the trough away from the feeder, or in other words, eventually into the position shown in phantom lines in Fig. 2. By a proper selection of the gears in the gear train connecting the two screw shafts any degree of outward movement away from the feeder can be achieved with any degree of descending movement of the gathering heads. Furthermore, by putting a hand crank or an electric motor drive on the shaft 634, a single operator can quickly lower the entire gathering machine trough throughout its whole length and simultaneously move it away from the feeder heads or conversely can move the trough upwardly and toward the feeders.

The machine operates in the following manner: At each of the feeders the loader shakes up a group of forms on the jogging table 86 and places them in the hopper 92 with the face of the forms against the plates 154 and 152 and with the spines against the supporting rails 196. The edges of the forms are kept in alignment by the side guide bars 184, it being appreciated that the hopper bars are properly adjusted to fit the forms to be fed. The angle of the hopper and the hopper accessories, such as the knife blade 223, the edge retainers 186 and 190 and so on, are of course adjusted to give proper operation. As the forms are fed through the machine and more are needed, they are simply placed upon the top of those already in the hopper and if some feeding difficulty is encountered because they do not flow through the hopper properly, the weighted follower 202 is placed upon the track 200 formed upon the guide bar 198 and slides downwardly under its own weight so that the nose 222 rests near the spine edge of the topmost form in the pile. With this weight in place, additional forms are simply added to those on the pile, thereby depressing the nose 222 of the follower so that they can settle against the support bars 196, after which the follower 202 is simply pulled out from beneath the stack until its nose 222 snaps upwardly. It is then released so as to fall against the topmost form.

With the machine in operation, the feed rolls 308 rotate continuously and the rotating cam shaft 140 causes the sucker heads 294 to swing inwardly and outwardly so that in one position they are brought flat against the lowermost form in the stack at a point close to the spine. In this position of the cam shaft 140, the oscillating pinch rolls 310 are in retracted position way from the feed rolls 308. A moment later, however, the sucker heads 294 swing backwardly and pull the spine edge of the form downwardly and backwardly into a position against or at least close to the feed rolls 308. At this moment the cam shaft 140 causes the pinch rolls 310 to swing into contact with the opposite face of the form and since these rolls are also rotating, the form is pulled by the pinch rolls 310 and feed rolls 308 from the bottom of the stack and fed in a downwardly and rearwardly direction.

The rearward swinging movement of the suction heads 294 is accompanied by a slight backward tilt of the lower edge of the movable hopper plate 152, thereby loosening the contact between the lowermost form and the one next to it so as to aid in the separation of the forms. Also this periodic oscillatory movement imparted to the bottom of the stack of forms causes them to settle into a more uniform relation as they progress down the hopper.

At about the time the suction heads are brought against the bottom of the stack of forms, the vacuum valve shown in Figs. 28 to 31 rotates to such position that the vacuum line 570 is connected to the transverse oscillating tube 264 which carries the suction heads. When the suction heads are at the opposite end of their stroke, that is in a position where the pinch roll 310 is about to press the form against the feed roll 308, the vacuum valve is moved to such position that the line 570 is disconnected from the oscillating tube 264 and this tube is vented to the atmosphere through the ports 586 and 582. Minor regulation of this vacuum cycle is made by adjusting the eccentric pin 588 and the needle valve 298 at the individual suction heads.

As a form passes downwardly, the spine is soon brought to the point where it is nipped between the feed rolls 400 of the caliper mechanism and the rubber idler rolls 402 in contact therewith. These rolls therefore continue to move the form in a downwardly and rearwardly direction over the apron 420 and into the trough 422. Meanwhile as the form passes between the feed roll 400 and the rudder idling rolls 402, it also passes between the caliper roll 426 and the gauge roll 432. If this caliper mechanism has been adjusted by rotating the screw 476 so as to position the gauge rolls a proper distance from the caliper rolls, and if a gauge block 592 with a slot 506 of the proper width has been chosen, and if this gauge block has been properly positioned along the body 456 of the caliper mechanism by adjusting the screw 496 with the knob 498, the caliper body will have moved the gauge block 492 to such position that as the cam shaft 140 causes the caliper blade 504 to swing upwardly momentarily, it will move freely through the slot 506 without touching the gauge block. On the other hand, if the form is slightly too thick or too thin, the slot 506 will not be perfectly aligned with the blade 504 and therefore the caliper body will be lifted and will actuate the push button switch 554 which stops the machine and lights the appropriate pilot light 556 at the particular feeder where trouble has been encountered. After clearing the difficulty, the operator presses the start button 508 to restart the machine.

The forms ejected over the apron 420 so that their spine edge is directed into the trough 422 come to rest and are soon swept in an endwise direction off the apron 420 by the advancing pin 606 of the conveyor mechanism. This pin carries the pile in contact with the table 424 and the support plate 600 of the trough in an end-

wise direction in such timed relation to the feeders that the pile arrives at the next successive feeder just as a form is being ejected by that feeder. It therefore falls on top of the pile and comes to rest just before it is picked up by the pin 606. Prior to the time it is picked up by the pin 606 the major portion of the bottom face of this form is in contact with the apron 420 since the apron is at a somewhat higher level than the stack of moving forms. The frictional resistance therefore causes the form lying upon the apron to remain substantially stationary as the pile advances beneath it until it is actually engaged by the pin 606. The forms therefore remain well aligned in the stack as they are carried forward by this advancing pin.

At the end of the machine the forms are delivered to the next successive device in the assembly chain, this device usually being a stitcher which secured the forms together prior to covering.

When it is desired to adapt the machine to handle forms of a larger or smaller size, it will be seen that it will be necessary to move the trough 422 downwardly and backwardly or upwardly and forwardly so as to permit the top edge of the forms to pass completely out of the feeder on to the apron 420 and on the other hand not go so far that they are not supported at their upper ends by the table 424. This adjustment is achieved by rotating the longitudinally extending shaft 634 either with a hand crank or an electric motor so as to cause the head casting 620 to move upwardly and downwardly simultaneously with the forward and backward movement of the slide 629 which carries the trough 422.

While I have shown and described a preferred embodiment of my invention, it will be apparent that numerous variations and modifications thereof may be made without departing from the underlying principles of the invention. I therefore desire, by the following claims, to include within the scope of the invention all such variations and modifications by which substantially the results of my invention may be obtained through the use of substantially the same or equivalent means.

I claim:

1. A machine for feeding forms one at a time from a stack of forms, comprising in combination a hopper for slidably holding a stack of forms, a cam shaft adapted to be driven continuously, a plurality of cams mounted on said cam shaft, a first set of continuously rotating feed rolls for passing a form through said machine, means operable by one of said cams for moving one of said sets of feed rolls toward and away from the other feed roll, means connected to a second of said cams and operable to transfer the lowermost form from the stack of forms to said set of rotating feed rolls as they are moved by said first cam toward each other, a second set of continuously driven feed rolls, a pair of caliper rolls, one of said caliper rolls being rockable away from the other of said caliper rolls in response to the thickness of the form passing between said second set of feed rolls, a caliper body connected to and movable by said rockable caliper roll, a caliper lever movable across the path of movement of said caliper body, means operable by a third of said cams and connected to move said caliper lever, said caliper body and said caliper lever being movable past each other when the machine is functioning properly and said caliper lever moving said caliper body when said machine is malfunctioning, and means operable by said caliper body for stopping the feeding operation when said caliper body is moved by said caliper lever upon a malfunctioning of the machine.

2. A machine for feeding forms one at a time from a stack of forms, comprising in combination a hopper for holding at an angle to the horizontal a stack of forms slidable on their spines, a cam shaft adapted to be driven continuously, a plurality of cams mounted on said cam shaft, a first set of continuously rotating feed rolls for

passing a form through the machine, one of said rolls being rockable toward and away from the other, means operable by one of said cams for moving said rockable feed roll toward and away from said other feed roll, means connected to a second of said cams and operable to transfer the lowermost form from the stack of forms to said set of rotating feed rolls as said rockable feed roll is moved by said first cam toward said second feed roll, said transfer means including a suction head engageable with a form, a source of vacuum, and timed valve means for connecting and disconnecting said vacuum source and said suction head, a second set of continuously driven feed rolls, a pair of caliper rolls, one of said caliper rolls being rockable away from the other of said caliper rolls in response to the thickness of the form passing between said second set of feed rolls, a caliper body connected to and movable by said rockable caliper roll, a caliper lever movable across the path of movement of said caliper body, means operable by a third of said cams and connected to move said caliper lever, said caliper body and said caliper lever being movable past each other when the machine is functioning properly and said caliper lever moving said caliper body when the machine is malfunctioning, and means operable by said caliper body for stopping the feeding operation when said caliper body is moved by said caliper lever upon a malfunctioning of the machine.

3. A machine for feeding forms one at a time from a stack of forms, comprising in combination a hopper for holding at an angle to the horizontal a stack of forms slideable on their spines, said hopper having a rockable plate defining its inner end, a cam shaft adapted to be driven continuously, a plurality of cams mounted on said cam shaft, a first set of continuously rotating feed rolls for passing a form through the machine, one of said rolls being rockable toward and away from the other, means operable by one of said cams for moving said rockable feed roll toward and away from said other feed roll, means operable by a second of said cams to transfer the lowermost form from the stack of forms to said set

of rotating feed rolls as said rockable feed roll is moved by said first cam toward said other feed roll, said transfer means including a suction head engageable with a form, a source of vacuum, timed valve means for connecting and disconnecting said vacuum source and said suction head, and a lever system for connecting said second cam and said suction head and said valve means, a reciprocable cam means operable from said lever system for rocking said hopper plate, a second set of continuously driven feed rolls, a continuously driven caliper roll, a gauging roll mounted to be rockable away from said caliper roll in response to the thickness of the form passing between said second set of feed rolls, a caliper body connected to and movable by said gauging roll, a caliper lever movable across the path of movement of said caliper body, means operable by a third of said cams and connected to move said caliper lever, said caliper body and said caliper lever being movable past each other when the machine is functioning properly and said caliper lever moving said caliper body when said feeder is malfunctioning, and means operable by said caliper body for stopping the feeding operation when said caliper body is moved by said caliper lever upon a malfunctioning of the machine.
